UNITED STATES PATENT OFFICE.

CLARENCE A. SNIDER, OF CLEVELAND, OHIO, ASSIGNOR TO THE SNIDER-HUGHES COMPANY, OF CLEVELAND, OHIO, A CORPORATION OF OHIO.

DUPLEX STEAM-PUMP.

SPECIFICATION forming part of Letters Patent No. 786,467, dated April 4, 1905.

Application filed June 20, 1904. Serial No. 213,236.

To all whom it may concern:

Be it known that I, CLARENCE A. SNIDER, a citizen of the United States, residing at Cleveland, in the county of Cuyahoga and State of Ohio, have invented a certain new and useful Improvement in Duplex Steam-Pumps, of which the following is a full, clear, and exact description, reference being had to the accompanying drawings.

10 The object of the invention is to produce a duplex steam-pump which shall be simpler and cheaper and less liable to get out of order than any of the duplex steam-pumps now in use, but which shall be no less efficient.

15 The invention relates to the steam-cylinders and their associated parts, which operate the water-pump pistons.

In pumps embodying my invention there is no steam-chest distinct from the cylinders 20 and no valve-operating mechanism outside of the cylinders or movable independent of the piston. The middle portion of each cylinder serves as the steam-chest for the other cylinder and contains a valve which is operated 25 directly by the piston to control the flow of steam between the middle part of each cylinder and the ends of the associated cylinder.

In the drawings, Figure 1 is a side elevation of a duplex steam-pump embodying my invention, the near steam-cylinder being shown 30 in vertical longitudinal section. Fig. 2 is a central horizontal sectional view of the two steam-cylinders. Fig. 3 is a longitudinal vertical section of one steam-cylinder looking in the direction of the other. Figs. 4, 5, 6 and 35 7 are respectively sectional plan views on line 4, 5, 6, and 7, respectively, of Fig. 8. Fig. 8 is an end view of said cylinders. Fig. 9 is a transverse sectional view of the two cylinders, 40 the section being taken in the plane indicated by line 9 of Fig. 2. Fig. 10 is a detached view of one of the pistons, showing the inner side of said piston—that is to say, that side which is toward the other cylinder. Fig. 11 45 is a detached view of the other piston, showing the outer side thereof. Figs. 12, 13 and 14 are transverse sectional views, respectively, in the planes indicated by lines 12, 13, and 14

of Fig. 10. Fig. 15 is a plan view of the valve and guide-arm in one cylinder. Fig. 16 is a 50 side elevation, partly broken away, of the part shown in Fig. 15.

The following is a description of the best embodiment of the invention now known to me:

Referring to the parts by letters, A and A' 55 represent two parallel steam-cylinders which are preferably formed in the same casting. The middle part of each cylinder is connected by two ports with each end of the other cylinder, these ports being formed, preferably, in 60 the metal between the cylinders. In other words, there are eight ports of this character—to wit, the ports C, D, E and F, which connect the middle part of cylinder A with opposite ends of cylinder A', and the ports G, 65 H, I, and J, which connect the middle part of the cylinder A' with opposite ends of the cylinder A. The ports C and E are inlet-ports through which steam flows to opposite ends of cylinder A', and the ports D and F 70 are exhaust-ports through which steam flows from opposite ends of the cylinder A'. The ports G and I are inlet-ports through which steam flows to opposite ends of cylinder A, and the ports H and J are exhaust-ports 75 through which steam flows from opposite ends of cylinder A. The port-openings c d e f of the ports C, D, E, and F, respectively, in the middle part of the cylinder A are arranged in a transverse zone, being confined 80 to an arc of about ninety degrees, including that part of the cylinder-wall which is nearest to the other cylinder. The port-openings at the opposite ends of these ports C, D, E, and F are found in the opposite ends of the other 85 cylinder, A', and are respectively indicated c' and e' (the inlet-port opening) and d' and f', (the exhaust-port openings.) The port-openings g, h, i, and j of the ports G, H, I, and J are similarly arranged in the middle part of 90 cylinder A'. The port-openings at the opposite ends of these ports in cylinder A are respectively indicated by g', i', h', and j'. The inlet-port openings c, g', e', and i' are placed near the ends of their respective cylinders, so 95 that they will never be covered by the piston-

heads. The outlet-port openings d , h , f' , and j' are placed at a greater distance from the ends of their respective cylinder and are placed in such positions that the piston-heads 5 as they near the ends of the cylinders will cover said ports, and thereby imprison some steam in the cylinder ends, which steam being compressed acts to stop the piston and prevent it from striking the ends of the cylinder. In the metal between the two cylinders is a centrally-placed and longitudinally-extended final exhaust-port K , which communicates with both cylinders through the port-openings k and k , which are located in 10 middle positions—that is to say, with two port-openings above and two below, as shown particularly in Figs. 3 and 9. Steam is admitted freely to the middle part of both cylinders through an initial inlet-port L , which 15 is always open.

In the cylinders A and A' are respectively the two pistons B and B' , which are alike in the following respects, to wit: Each has two heads b and b' , which are fitted to the cylinder, 20 and between them there is a body portion of smaller diameter than said heads, this body being preferably a hollow shell. The space between the piston-heads in each cylinder serves as a steam-chest for the other cylinder. 25 In the body part of each piston and on that side thereof which is most remote from the other cylinder is a longitudinal slot b^3 , and directly opposite this slot there is an inclined slot b^4 , and in the body part of the piston is 30 a recess b^5 , with which both of said slots communicate. A guide-arm M in each cylinder is rigidly fastened to the wall thereof and projects through the slot b^3 into the recess b^5 , and one of the purposes of this arm is to prevent 35 the piston from turning—in other words, to compel it to move in an absolutely-straight line.

N represent valves, of which there is one in each cylinder. Each has an arcual face fitting the curvature of the cylinder and is long enough to cover the group of five port-openings in the middle part of the cylinder in which it lies, and it does cover them all when in its middle position, as shown at the right of Fig. 40 9. It has a stem n , which passes through the inclined slot b^4 of the cylinder into the recess b^5 and lies between the bifurcated ends m of the arm M , whereby it is prevented from moving endwise with the piston, but is thereby 45 compelled by the inclined slot b^4 to swing up and down as the piston moves to and fro. This valve contains the usual D -recess n' , which is adapted to establish communication between the final exhaust-port opening k and the 50 either of the exhaust-port openings above and below it. When the valve is in its lowest position, it is establishing communication between the final exhaust-port opening k and the exhaust-port below it. At this time the valve 55 covers the lower inlet-port opening, but does

not cover the upper inlet-port opening, and when the valve is moved to its upper position it opens the lower inlet-port opening and closes the upper inlet-port opening and the lower exhaust-port opening and establishes communication between the upper exhaust-port opening and the final exhaust-port opening k . 70

The mode of operation of the described mechanism will be understood from the following description, which assumes the parts 75 to start from the position shown in Figs. 2 and 9. The piston B' is at the rear end of cylinder A' , and piston B is in the middle of cylinder A and moving in the direction of the arrow. Steam is being freely admitted into both 80 cylinders between the piston-heads b and b' through the port L , whereby the space between these two piston-heads in each cylinder serves as a steam-chest. Steam from the cylinder A' is flowing through the upper port G 85 to the front end of the cylinder A , thereby moving the piston B therein rearward. At the same time the exhaust-port J is connected with the port-opening k , which permits steam to flow to the final exhaust-port K from 90 the front end of the cylinder A . All of the middle port-openings in cylinder A are closed; but a still further movement of the piston B will cause the valve N , associated with it, to move and to open up the port C , so that steam 95 will flow from the middle part of the cylinder A to the rear end of the cylinder A' , at the same time establishing communication between the port K and the exhaust-port F , and consequently the piston B' begins to move toward the front end of the cylinder A' . The 100 parts are so arranged that when either piston is at the middle of its path of travel the other piston is at one end or the other of its path. When the piston B' reaches the middle of its 105 path of travel, it has moved the valve so that all of the port-openings guarded by it are closed, the piston B having by that time reached the rear end of cylinder A . A still further movement of this piston B' moves the associated 110 valve, so as to admit steam to the rear end of the cylinder A and to permit the flow of steam to the front end of the same cylinder, whereupon piston B begins its rearward movement. These operations go on indefinitely, each piston moving the valve in its cylinder, which 115 controls the flow of steam to and from the opposite cylinder.

It will be understood that in the particular embodiment of the invention shown the two 120 inclined slots b^3 in the two pistons are parallel when the parts are assembled, or otherwise the parts would not operate as described. It will be understood, further, that it is not my desire or intention to be limited to any 125 greater extent than is plainly expressed in the claims to the specific mechanism shown and herein described. It is my desire, therefore, that my claims shall be construed to be commensurate with the breadth of the invention. 130

tion and that they shall not be limited to any details beyond those which are plainly specified in the appended claims.

Having described my invention, I claim—

- 5 1. In a steam-pump, the combination of two cylinders A A', each having an initial inlet-port, and a final outlet-port, and there being eight other ports which connect said cylinders, to wit; the inlet-ports C, E, which connect the middle part of cylinder A with the opposite ends of cylinder A', the inlet-ports G, I, which connect the middle part of cylinder A' with opposite ends of A, all of the port-openings in the ends of said cylinders being close 15 to said ends, two outlet-ports, D and F which connect the middle part of cylinder A with the opposite ends of cylinder A' and the outlet-ports H and J which connect the middle part of cylinder A' with the opposite ends of cylinder A, the port-openings of these outlet-ports in the ends of the cylinders being at a considerable distance from said ends whereby they will be covered by the piston-heads as 20 said heads near the ends of said cylinder, with a piston in each cylinder having two heads fitted to the cylinder and an intermediate body portion of smaller diameter, means preventing the rotation of said piston, sliding valve in each cylinder operable by the piston in an 25 arcual path, and means preventing the longitudinal movement of the valve in said cylinder.
2. In a pump, the combination of two cylinders, each provided with an initial inlet-port, a final outlet-port, four ports which lead from the middle part of each cylinder to opposite ends of the other cylinder, two inlet-port openings close to opposite ends of the cylinder, and two outlet-port openings near 30 opposite ends of the cylinder but at such a distance from said ends that they will be covered by the piston-heads when the piston nears the ends of the cylinder, all of the four port-openings last mentioned being in communication with the four ports which lead from the middle part of the other cylinder, with a piston having two heads, fitted to said cylinder and lying on opposite sides of the middle ports, and a connecting body portion 35 of smaller diameter, means preventing the rotation of said piston, and a valve in the cylinder operable by the piston.
3. In a pump, the combination of two cylinders, each having an initial inlet-port, and
- 55 a final outlet-port, and ports connecting the middle part of each cylinder with the ends of the other cylinder, a piston in each cylinder consisting of two separated heads, fitted to the cylinder and lying at all times on opposite sides of said middle ports, and an intermediate body portion of smaller diameter, in which is a straight longitudinal slot, an inclined slot and an interior recess with which both slots communicate, a valve having a stem which extends through the inclined slot into 60 said interior recess, an arm fixed to the inside of the cylinder and passing through the straight slot into said recess, and engaging with the stem of the valve, whereby said arm prevents the piston from turning and prevents the valve from moving lengthwise of the cylinder.
4. The combination of two cylinders each having an initial inlet-port communicating with the middle part thereof, and four ports 65 leading from the middle part to the opposite ends of the other cylinder, and a final outlet-port for each cylinder, with a piston in each cylinder having a body portion and heads fitted to the cylinder lying on opposite sides of said port, and there being a straight slot in the one side of the body part of said piston, and an inclined slot in the opposite side of said piston, a fixed arm in the cylinder entering said straight slot, a valve in each cylinder having a stem which enters said inclined slot, and means preventing the endwise movement of said valve with its operating-piston.
5. The combination of two cylinders each having an initial inlet-port and four ports 70 leading from it to the opposite ends of the other cylinder, and a final outlet-port for each cylinder, with a piston in each cylinder having a body portion and heads fitted to the cylinder lying on opposite sides of said ports, 75 there being a straight slot and an inclined slot in the body part of said piston, a D-valve for each cylinder having a stem which enters said inclined slot, and a fixed arm which enters the straight slot and has a bifurcated inner end, which embraces the stem of said valve.
- 80 In testimony whereof I hereunto affix my signature in the presence of two witnesses.

CLARENCE A. SNIDER.
